DESIGN FOR A SOLDERLESS ELECTRICAL CONNECTOR

Charles A. Martin, Lynbrook, N. Y.

Application June 19, 1944, Serial No. 114,093

Term of patent 3½ years

(Cl. D26—1)

To all whom it may concern:

Be it known that I, Charles A. Martin, a citizen of the United States, residing at 27 Piccadilly Downs, Lynbrook, in the county of Nassau and State of New York, have invented a new, original, and ornamental Design for a Solderless Electrical Connector, of which the following is a specification, reference being had to the accompanying drawing, forming a part thereof.

In the drawing:

Fig. 1 is a perspective view of a solderless electrical connector, showing my new design.

Fig. 2 is a side elevational view.

Fig. 3 is a top plan view.

Fig. 4 is a bottom plan view.

Fig. 5 is an end elevational view looking in the direction of the arrows 5—5 of Fig. 2; and

Fig. 6 is an end elevational view looking in the direction of the arrows 6—6 of Fig. 2.

I claim:

The ornamental design for a solderless electrical connector, as shown.

CHARLES A. MARTIN.
